DESIGN FOR A SELF-SERVICE DISPLAY CASE

Joseph Stuart Hill, Hillwood Lakes, N. J., assignor to C. V. Hill & Company, Incorporated, Trenton, N. J., a corporation of New Jersey

Application October 30, 1941, Serial No. 103,959

Term of patent 14 years

To all whom it may concern:

Be it known that I, Joseph Stuart Hill, a citizen of the United States, residing at Hillwood Lakes, in the county of Mercer, State of New Jersey, have invented a new, original, and ornamental Design for a Self Service Display Case, of which the following is a specification, reference being had to the accompanying drawing, forming part thereof.

Fig. 1 is a perspective view of a self service display case embodying my new design;

Fig. 2 is a top plan view of the same; and

Fig. 3 is an end elevational view of the same.

I claim:

The ornamental design for a self service display case, as shown.

J. S. HILL.
